UNITED STATES PATENT OFFICE.

FRANK FONTANA, OF SAN FRANCISCO, CALIFORNIA.

DESIGN FOR A CLOCK FACE.

Application filed October 10, 1927. Serial No. 23,708. Term of patent 3½ years.

To all whom it may concern:

Be it known that I, FRANK FONTANA, a citizen of the United States, and a resident of the city and county of San Francisco, State of California, have invented a new, original, and ornamental Design for a Clock Face, of which the following is a specification, reference being had to the accompanying drawing, forming part thereof.

The drawing is a front view of the clock face embodying my design.

I claim:

The ornamental design for a clock face substantially as shown.

FRANK FONTANA.
